UNITED STATES PATENT OFFICE.

JOHN W. GRANGER, OF PHILADELPHIA, PENNSYLVANIA.

CARRIER-PLATE FOR HOOKS AND EYES.

No. 857,781.

Specification of Letters Patent.

Patented June 25, 1907.

Application filed October 11, 1904. Serial No. 228,079.

To all whom it may concern:

Be it known that I, JOHN W. GRANGER, a citizen of the United States, residing in Philadelphia, Pennsylvania, have invented certain 5 Improvements in Carrier-Plates for Hooks and Eyes, of which the following is a specification.

The object of the invention is to provide a carrier plate of novel construction for the 10 reception of the hooks, eyes and display card, by means of which these latter may be fed to a machine and properly sewed in position on said card.

It is further desired to provide a simple 15 and efficient device for properly holding the display card in the carrier plate.

These objects I attain as hereinafter set forth, reference being had to the accompanying drawings, in which:—

20 Figure 1, is a plan view of the upper face of one member of my improved carrier plate, showing the various grooves therein and also illustrating certain of the hooks and eyes in the positions occupied by them prior to their 25 mounting upon a display card; Fig. 2, is a plan view of the upper member of my improved carrier; Fig. 3, is a plan view of the display card which it is desired shall be produced by the use of my improved carrier, 30 showing two series of hooks and loop eyes mounted in position, together with a series of invisible eyes mounted between said two first series and held in position independently thereof, and, Fig. 4, is a sectional elevation 35 taken through my improved carrier and showing the relative position of a display card therein.

By my invention I provide a carrier by 40 means of which hooks and eyes may be so mounted upon a display card that any desired number of the invisible eyes may be removed without in any way affecting the fastening means either of the hooks or of the loop eyes also carried upon said card.

45 In the above drawings, A represents a piece of pasteboard or paper upon which two series of hooks *a* are mounted; these being respectively in engagement with two series of loop eyes *a'*. Between each series of hooks 50 and loop eyes is a line or series of invisible eyes *a²*. The hooks, as noted, are in engagement with the loops of their respective loop eyes and the latter are held in position upon the display card A by a line of chain stitching

a³ passing through the card and their thread 55 bends. The hooks are similarly held in position by a line *a⁴* of chain stitching, while two other lines of similar stitching *a⁵* pass through the thread bends of the invisible eyes and thereby hold them in place between the two 60 sets of hooks and loop eyes.

For the purpose of assembling the above mentioned hooks and eyes upon the display card, I provide the carrier B, which consists of a lower plate B' and an upper plate 65 B². The lower plate has upwardly projecting flanges or edges *b* and *b'* extending along two of its opposite sides, and the blank display card A is held in position between these edges by means of a flat spring *b²*, said spring 70 being curved outwardly so as to engage the edge of the card and being held to one of the edges of the plate by means of a screw or rivet *b³* passing through one of its ends. The amount of movement of its opposite end is 75 limited by a pin *b⁴* and, as shown, I preferably provide a recess *b⁵* in the plate for said spring. In order that each card A may, when placed in the carrier, occupy a certain, 80 definite position, I provide two guide lugs *b⁶* 85 along one side of the plate and a third lug *b⁷* placed so as to engage a side of the card at right angles to that engaged by the lugs *b⁶*.

Extending longitudinally of the plate B' are six slots or recesses *c*, *c'*, *c²*, *c³*, *c⁴* and *c⁵*, 85 each of which extends completely through the plate so as to permit the passage of the needle of a sewing machine of the type illustrated in a patent granted to me February 7, 1893, No. 491,281. Extending between each 90 pair of the slots *c* and *c'* and *c⁴* and *c⁵* are a series of grooves or recesses *c⁶*; their number being equal to the number of hooks which it is desired to mount on any one card. At the 95 end of these slots adjacent to the longitudinal slots *c* and *c⁵* respectively, are enlarged and substantially semi-circular portions *c⁷* for the reception of the thread holding eyelets of the loop eyes. Extending through the rib of metal between the two longitudinal slots *c²* 100 and *c³* are a series of transverse grooves *c⁸* for the reception of the central portions of the invisible eyes; it being noted that there are two of these grooves to each opposite pair of the grooves *c⁶*.

105 For holding the hooks, eyes and display card in position in the lower member B' of the carrier during the passage of the same

through the sewing machine, I provide the upper or cover plate B², which preferably consists of a flat plate of metal made with a projecting lug d placed to enter a recess in 5 the flange b' of the lower member B' and having a portion cut away to prevent its interference with the spring b². There is also a hole or recess d' for the reception of the lug b⁷ and a series of longitudinal slots d² so 10 placed as to be directly over the slots c to c⁵ inclusive, of the plate B'.

When it is desired to assemble hooks and eyes upon display cards, the former are mounted in the lower plate B', as shown in 15 Fig. 1; it being noted that in every instance the thread receiving bents of the various hooks and eyes extend over their appropriate longitudinal slots. After all of the transverse slots c⁶ and c⁸ have been filled with their 20 proper hooks and eyes, I place a sheet of cardboard or stiff paper A on the plate B', holding it in the desired position by means of the spring b². The upper plate or cover is then placed in position over the card and the 25 carrier is passed through a sewing machine having six needles, which respectively operate through the slots d² of the upper plate B² and the slots c to c⁵ inclusive, of the lower plate, thereby simultaneously stitching the 30 various hooks and eyes to their display card, so that this latter appears as illustrated in Fig. 3.

I claim as my invention:

A carrier for holding hooks, eyes and a card during the assembling of the same, said card consisting of an upper and a lower plate, of which one is provided with longitudinally extending needle slots, and a plurality of series of grooves transverse to said slots, two series of the grooves being adapted 35 to receive hooks and loop eyes and another series being shaped to receive invisible eyes, the grooves of said latter series all terminating in two of the longitudinal slots independently of the other slots and said other slots 40 extending in pairs adjacent to the respective ends of the series of grooves for the hooks and loop eyes, a stop on one side of the carrier placed to limit the movement of a card between the plates, a spring of sheet material 45 held to the carrier at one end and placed on the side thereof opposite the stop, said spring being convexly bent so as to directly engage a card between the plates, with a stop placed to be engaged by the free end of the spring 50 for limiting the movement thereof, substantially as described.

In testimony whereof, I have signed my name to this specification, in the presence of two subscribing witnesses.

JOHN W. GRANGER.
